CLAIM

The ornamental design for an absorber of electrical noise, as shown and described.

DESCRIPTION

FIG. 1 is a front and upper left perspective view of an absorber of electrical noise showing my new design mounted on a ribbon cable. The broken line showing of the ribbon cable is included for the purpose of illustrating environmental elements only and forms no part of the claimed design;

FIG. 2 is a front and upper left perspective view of an absorber of electrical noise showing the design;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a right side elevational view thereof, the left side elevational view thereof being a mirror image.
